UNITED STATES PATENT OFFICE.

JAMES C. KARNES, OF BUFFALO, NEW YORK.

FIRE-CONTROL SYSTEM FOR ORDNANCE.

Application filed May 14, 1927. Serial No. 191,470.

(GRANTED UNDER THE ACT OF MARCH 3, 1883, AS AMENDED APRIL 30, 1928; 370 O. G. 757.)

The invention described herein, if patented, may be manufactured and used by or for the Government for governmental purposes without the payment to me of any royalty thereon.

This invention relates to a fire control system for ordnance.

The observation of artillery fire with a view to calculating the lateral and vertical corrections necessary to place the burst on the target can not be carried on accurately at long ranges. As a result the airplane has been introduced to enable the observer to obtain data from the vicinity of the target.

The object of this invention is to provide a system of fire control wherein the data to be obtained by an aerial observer may be rapidly determined in a form available for immediate transmission to the battery station and the data may be applied in a novel manner to ascertain the range and deflection error.

With the foregoing and other objects in view, my invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawings, wherein:

Figs. 1 and 2 are respectively views in side and end elevation of the observing instrument;

Fig. 3 is a detail view of the reticule pattern;

Fig. 4 is a view of the plotting paper before entering data;

Fig. 5 is an illustrated view of the reticule for a particular situation;

Fig. 6 is a view of the plotting paper on which is entered the data shown in Fig. 5;

Figs. 7 and 8 are views corresponding to Figs. 5 and 6 and representing a different situation;

Fig. 9 is a plan view of the deflection protractor;

Fig. 10 is a view showing the manner of applying direction and deflection protractors to the problem presented in Fig. 8, certain of the coordinate lines of the plotting paper being omitted to avoid confusion.

Referring to the drawings by numerals of reference:

The elementary steps involved in correcting artillery fire from observation of the burst of the projectile comprise a designation of the burst point in terms of reference either to the target or the gun so that the burst may be plotted and the corrective data measured and applied.

The apparatus employed in conjunction with the present system comprises a number of independent elements, namely, a spotting instrument A, a sheet of plotting paper B, a direction protractor C and a deflection protractor D which is longitudinally graduated in values of range and transversely graduated in values of angular lateral measurements.

The spotting instrument A, in the form of a telescope, is mounted in an airplane and is manned by an observer. It is provided with a pendulum a carrying a scale b registering against an index c on the instrument and serving to afford a measure of the angle of depression m to the target. The reticule d in the observer's telescope (Fig. 3) is of a distinctive pattern and consists of a clock dial e within which are a number of concentric circles f representing angular differences of 1° from the axis of the instrument and serving to measure the angle of deviation of burst from the line of sight as represented by the letter n in Fig. 6.

The plotting paper B (Fig. 4) is prepared with a ground line g, a flight line h which may be predetermined and an altitude line i whose point of intersection k with the ground line represents the position of the target E (Figs. 5, 6 and 7).

Assuming that the plane is traveling along the battery-target course at a predetermined altitude the observer in sighting his telescope on the target locates the target in the center of the field. When a burst F appears as indicated in Fig. 5 he transmits the angle of depression m, the clock number which indicates the direction of the burst with respect to the target, and the number of the circle which indicates the angular variation n from the line of sight. This data revealed by the burst shown in Fig. 5 is plotted on the paper B as seen in Fig. 6. The battery station in this instance thereby obtains a measure of the distance X-Y and this value in terms of

range is known from the scale of the plotting paper.

In those cases where the burst does not occur on the meridian line it is necessary to introduce the protractors into the solution as seen in Figs. 8 and 10 wherein the data shown in the reticule of Fig. 7 is plotted. The direction protractor being laid on the paper with the two o'clock line on the ground line ⁵⁰ *g*, the deflection protractor is placed over it in such a manner that its zero line is over the meridian line of the direction protractor and the proper range line passes through the target. The correction for range may be directly read from the range scale and the correction for lateral deflection may also be directly read therefrom in angular values.

While observations should preferably be made when the plane is on the battery-target course a burst may be reported when the plane is off the coarse as the observer may readily interpret the proper direction of the point of burst with respect to the target by reference to the course indicator or compass carried by the plane.

The data to be transmitted is available in convenient form as it will only be necessary to report a series of numbers. Any deviation from predetermined altitude may be expressed in code numbers.

I claim:

1. In a fire control system, the combination with an aircraft of a telescope having a reticule presenting a direction dial and a plurality of concentric circles representing angular variations from the axis of the telescope and means associated with the telescope for measuring the angle of depression.

2. In a fire control system, the combination with an aircraft of a telescope having a reticule presenting a direction dial and means for indicating angular variations from the axis of the telescope and means associated with the telescope for measuring the angle of depression.

3. A method of ascertaining the range and

deflection error of a burst point with respect to a target which includes plotting the burst point from values of altitude, of angle of depression of target and an angle of deviation of burst all with respect to the point of observation on a plotting paper presenting a ground line and a target point on said line, establishing a battery-target course through the target point by directional reference of the point of burst with respect to the target, and applying a protractor having range and deflection scales.

4. A method of fire control for ordnance which includes determining from an observation point the altitude of said point, the angle of depression to the target, the angle of deviation of burst and the direction of burst with respect to a substantially vertical plane through point and target, plotting the position of target and burst from the data obtained, establishing the battery-target course by applying a clock protractor with its center over the plotted position of the target and with the directional indication of the burst over the plotted position of burst, and measuring the range and deflection differences between the plotted position of the burst and target.

5. A method of fire control for ordnance which includes determining from an observation point the angle of depression to target, the angle of deviation of burst and the direction of burst with respect to a substantially vertical plane through point and target, determining the altitude of the observation point; plotting the position of target and burst from the data obtained, establishing the battery target course by applying a clock protractor with its center over the plotted position of the target and with the directional indication of the burst over the plotted position of burst and measuring the range and deflection difference between the plotted position of the burst and target.

JAMES C. KARNES.
